TEXTILE FABRIC

Ellen Freitag, Long Island, N. Y.

Application July 13, 1949, Serial No. 3,881

Term of patent 3½ years

(Cl. D92—1)

To all whom it may concern:

Be it known that I, Ellen Freitag, a citizen of no country, residing in Long Island, county of Queens, and State of New York, have invented a new, original, and ornamental Design for a Textile Fabric, of which the following is a specification, reference being had to the accompanying drawing, forming part thereof.

The figure on the drawing is a plan view of a textile fabric showing my new design. The design unit is contained between the dot and dash lines, which unit is repeated in staggered relation as indicated.

I claim:

The ornamental design for a textile fabric, substantially as shown and described.

ELLEN FREITAG.
